COMBINED CLIP DISPENSER AND PENCIL HOLDER

Robert M. Leedy, 7 Martindale Road,

Short Hills, N.J. 07079

Filed July 7, 1971, Ser. No. 165,808

Term of patent 14 years

Int. Cl. D19—02

U.S. Cl. D74—5 A

FIG. 1

FIG. 2

FIG. 3

FIG. 4

FIG. 1 is a perspective view of a combined clip dispenser and pencil holder showing my new design;

FIG. 2 is a top view thereof;

FIG. 3 is a perspective view of another embodiment of the combined clip dispenser and pencil holder shown in FIG. 1 wherein the pencil holder is shown at an angle; and

FIG. 4 is a top view thereof.

The undisclosed sides of the combined clip dispenser and pencil holder are plain and unornamented.

I claim:

The ornamental design for a combined clip dispenser
